US00D994682S

(12) **United States Design Patent** (10) **Patent No.:** **US D994,682 S**
Amini et al. (45) **Date of Patent:** **** Aug. 8, 2023**

(54) **ELECTRONIC DEVICE WITH GRAPHICAL
USER INTERFACE**

(71) Applicant: **Apple Inc.**, Cupertino, CA (US)

(72) Inventors: **Mani Amini**, San Francisco, CA (US);
Patrick Lee Coffman, San Francisco, CA (US); **Elizabeth Caroline Cranfill**, San Francisco, CA (US); **Vitalii Kramar**, Mountain View, CA (US); **Marcel Van Os**, Santa Cruz, CA (US); **Eric Lance Wilson**, San Jose, CA (US)

(73) Assignee: **Apple Inc.**, Cupertino, CA (US)

(**) Term: **15 Years**

(21) Appl. No.: **29/760,832**

(22) Filed: **Dec. 4, 2020**
